(57) **CLAIM**

The ornamental design for a mathematical colored-numbered puzzle double board game as shown and described.

DESCRIPTION

FIG. 1 is a front view in the open position of a mathematical colored-numbered puzzle double board game according to my new design;

FIG. 2 is a rear view in the open position of the mathematical colored-numbered puzzle double board game of FIG. 1;

FIG. 3 is a front perspective view in the open position of the mathematical colored-numbered puzzle double board game of FIG. 1;

FIG. 4 is a rear perspective view in the open position of the mathematical colored-numbered puzzle double board game of FIG. 1;

FIG. 5 is a top view in the open position of the mathematical colored-numbered puzzle double board game of FIG. 1;

FIG. 6 is a left side view in the closed position of the mathematical colored-numbered puzzle double board game of FIG. 1; and,

FIG. 7 is a right side view in the closed position of the mathematical colored-numbered puzzle double board game of FIG. 1.

The broken lines seen in the figures depict portions of the mathematical colored numbered puzzle double board game which form no part of the claimed design.

1 Claim, 6 Drawing Sheets
